UNITED STATES PATENT OFFICE.

WILLIAM NELSON LE PAGE, OF SAN FRANCISCO, CALIFORNIA.

ARMOR FOR VESSELS, FORTS, &c.

SPECIFICATION forming part of Letters Patent No. 314,456, dated March 24, 1885.

Application filed December 13, 1884. (No mode.)

To all whom it may concern:

Be it known that I, WILLIAM N. LE PAGE, of San Francisco, in the county of San Francisco and State of California, have invented 5 certain new and useful Improvements in Armor for Vessels, Forts, &c.; and I do hereby declare the following to be a full, clear, and exact description of the invention, such as will enable others skilled in the art to which 10 it appertains to make and use the same.

My invention relates to an improvement in armor for ships, batteries, &c.

It is well known that a shot will not penetrate a yielding obstruction as readily as it 15 will a rigid one, and for this reason springs of different forms have hitherto been interposed between the plates and hull of a vessel, or between the plates themselves, to admit of their yielding when struck by a cannon-shot. 20 It is also well known that hardness combined with toughness of fiber tends to render a solid the most impenetrable.

The object of my present invention is to provide an armor which shall combine the advantages of a yielding, hard, and tough armor, 25 and which is therefore well adapted to protect ships, batteries, and forts against the destructive action of missiles.

With these ends in view my invention consists in certain features of construction and 30 combinations of parts, as will be hereinafter described, and pointed out in the claims.

In the accompanying drawings, Figure 1 is a sectional view of a portion of the armor; and 35 Fig. 2 represents a vertical cross-section of a vessel provided with the armor.

The gist of my invention consists in an armor formed of the desired thickness by alternating one, two, or more layers of plates constructed of iron, steel, or other suitable material, with a cement or composition of a particular nature, covering the outside with a plate of chilled steel, and interposing springs between the hull and the plating thus formed.

40 A represents one, two, or more layers of iron or steel plates, or the plates may be formed of othersuitable material, bolted firmly together. The number of layers is preferably three. B represents a layer of cement or com- 45 position resting in close contact with the outside of the layers A, and composed of asbestos,

wool or hair, cork, and glue. The glue preferred is "Le Page's Liquid Fish Glue." On the outside of the layer of cement a second series of layers, A', similar to the layers A, are 55 secured, then a second layer of cement, B', and so on until the thickness is sufficient to withstand any shock which the armor is liable to receive. Outside of the last layer of plates a plate of chilled steel, C, is secured, and between the inside layer, A, and the hull of the vessel D, or other surface to be protected, a set of springs, E, is secured. The springs E are preferably of the heavy coiled form, and are secured to the inside layer, A, and a suitable covering, F, by any approved means. The armor as thus constructed is bolted or otherwise secured to the sides of a vessel, or face of a battery or fort.

The shot striking the chilled-steel coating 70 obliquely will glance, the hardness of the metal and the yielding of the armor preventing it from gaining any hold thereon. The shot striking the armor at right angles thereto will be seriously obstructed in penetrating the 75 steel coating, and in penetrating the layers of plates beneath it will be more effectually obstructed on account of the cement, which prevents the plates from flying in pieces, and offers great resistance in itself on account of its 80 combined hard fibrous and elastic nature. In addition to the effectual resistance thus obtained, the yielding of the outer portion of the armor by the compression of the heavy springs serves to prevent great penetration, and the 85 shot is brought to rest before it reaches the hull of the boat or face of the battery, fort, &c. The layers of cement, furthermore, prevent the plates from cracking for a great distance when struck, and, in case of vessels, prevent the water from reaching the side of the hull through cracks or breaks in the outer layers of armor; and the armor, as a whole, is 90 much lighter than armors hitherto constructed having the same resistance.

I do not wish to limit myself to any particular number of layers in a plate-section, nor to any particular material, nor to any particular thickness of plates or cement, as in some instances I may find it advisable to use a great 100 number of thin layers of plates of different materials; and it is evident that other arrange-

ments of the layers than those shown might be resorted to without departing from the spirit and scope of my invention.

Having fully described my invention, what I claim as new, and desire to secure by Letters Patent, is—

1. The combination, with an armor for vessels, forts, &c., consisting, essentially, of alternate layers of metal plates and cement, of 10 springs interposed between the armor and the hull or other surface to be protected, substantially as set forth.

2. An armor for vessels, forts, &c., consisting, essentially, of alternate layers of plates 15 and cement, having an outside covering of chilled steel and a backing composed of springs, substantially as set forth.

3. An armor for vessels, forts, &c., consist-

ing of a series of metal plates and an interposed filling of cement, the latter being composed of asbestos, wool or hair, and glue. 25

4. In an armor for vessels, forts, &c., the combination, with a layer of cement composed of asbestos, wool or hair, cork, and glue, of layers of plates located on the outside and inside of the layer of cement, a yielding backing, and a chilled-steel face, substantially as set forth. 25

In testimony whereof I have signed this specification in the presence of two subscribing witnesses. 30

WILLIAM NELSON LE PAGE.
